ELEVATOR CONTROL SYSTEM

Eivind U. Lassen, Whitefish Bay, Wis., assignor to
Cutler-Hammer, Inc., Milwaukee, Wis., a corporation of Delaware

Application July 10, 1939, Serial No. 283,542

4 Claims. (Cl. 187—29)

This invention relates to control systems for electric elevators and the like, and is particularly applicable to means for stopping and maintaining the elevator car level with any of its several landings.

The patent to G. C. Brown, No. 1,961,133, of June 5, 1934, discloses an automatic leveling control system for elevators and the like having electronic control means which provides for automatic leveling of the elevator car when it is within a given distance from the landing at which it is to be stopped. In this system a single dead zone is provided at each of the landings and the elevator is stopped as the same moves into such zone. The dead zone must be relatively narrow in order to obtain accurate leveling, and in practice it has been found that unless a low and constant landing speed is employed it is difficult to effect stopping within the dead zone without one or more re-leveling operations.

The present invention has among its objects to provide an improved controller of the type disclosed in the aforementioned patent which is adapted for use in connection with elevators having high landing speeds and which reduces to a minimum the number of re-leveling operations required to effect stopping of the elevator car within a relatively narrow dead zone.

The accompanying drawing illustrates an embodiment of the invention which will now be described, it being understood that various modifications may be made in the embodiment illustrated without departing from the spirit and scope of the appended claims.

In the drawing,

Figure 1 is a diagrammatic view of a control system embodying the invention, and

Fig. 2 is a diagrammatic representation of certain of the operating characteristics of the control means shown in Fig. 1.

Referring to Fig. 1, the same illustrates a reversible motor M for raising and lowering an elevator car C within a hatchway having a plurality of floor landings, one of which is indicated by reference character F. Motor M may be of the squirrel cage induction type to be supplied with current from a polyphase supply circuit indicated by lines L¹, L² and L³. One terminal of motor M is permanently connected to line L¹ and a pair of normally open double pole reversing switches 1 and 2 are provided for selectively establishing reverse power connections between the other two terminals of said motor and lines L² and L³. Each of the switches

1 and 2 is provided with an operating winding a and a set of normally open auxiliary contacts b and it is assumed that switch 1 provides for operation of motor M in its up direction, and 5 that switch 2 provides for operation of said motor in its down direction. Motor M is provided with a brake B which is normally set and is releasable by a winding 3 which is permanently connected across two of the terminals of motor M.

The reversing switches 1 and 2 are selectively controlled by a car switch CS having stationary contacts 5 to 9, inclusive, and movable contacts 10 to 15, inclusive. Said movable contacts are electrically connected and are mounted upon a drum which is movable in opposite directions out of an intermediate off position into positions indicated by reference characters U and D. The car switch CS also controls a relay 16 which 20 in turn controls a relay 17, and as hereinafter set forth said relays provide for control of a floor leveling mechanism. Relay 16 is provided with an operating winding 16^a, a set of normally open contacts 16^b and a set of normally closed contacts 16^c, and relay 17 is provided with an operating winding 17^a, a set of normally open contacts 17^b and a set of normally closed contacts 17^c.

The leveling control mechanism includes a 30 pair of normally open electromagnetic relays 18 and 19 for selectively establishing maintaining circuits for reversing switches 1 and 2. Relay 18 is provided with an operating winding 18^a which is adapted to be energized from a transformer T¹ through a tube 20 and relay 19 is provided with an operating winding 19^a which is adapted to be energized from a transformer T² through a tube 21. The tubes 20 and 21 are of the gaseous electron discharge type, and the 40 former tube is provided with a cathode 20^a, an anode 20^b and a control grid 20^c, while the latter tube is provided with a cathode 21^a, an anode 21^b and a control grid 21^c. The cathodes 20^a and 21^a may be heated in any well known manner and the grids 20^c and 21^c are subjected to control by an A. C. potential derived from a transformer 22 and also by a D. C. potential derived from a rectifier 23. The primary windings of transformers T¹ and T² are permanently 50 connected across lines L¹ and L³ and the secondary windings thereto are normally connected to the cathodes 20^a and 21^a by contacts 16^c of relay 16.

Transformer 22 is mounted upon the elevator 55 car C and is provided with an E-shaped core

member 24 having on its outer legs windings 24^a and 24^b, respectively, and on its center leg windings 24^c and 24^d. Mounted in the hatching way and coplanar with the face of core 24 are armatures 25, one of such armatures being provided for each floor landing where it is desired to obtain automatic leveling of the elevator car. When armature 25 is opposite the core 24 it reduces the reluctance of the magnetic circuit of the transformer, and thus increases the electromagnetic coupling between coils 24^a and 24^b, on the one hand, and the center coils 24^c and 24^d on the other hand. The coils 24^c and 24^d are connected in series across lines L¹ and L² and they are wound in such a manner that the fluxes which they induce in the center leg cancel each other so as to normally produce no resultant flux in said center leg. On the other hand, if an armature 25 bridges only the lower leg and the center leg of core 24 as indicated in dotted lines, a flux passes through the lower and center legs which induces a voltage of a certain phase relation with respect to the voltage of the coils 24^a and 24^b in the coils 24^c and 24^d, whereas if the armature 25 bridges the upper and center legs of said core a voltage is induced in the coils 24^c and 24^d which is opposite in phase to the first mentioned induced voltage.

Rectifier 23 is supplied with current from a transformer T³ which is permanently connected across lines L¹ and L², and said rectifier has a permanent resistance R¹ and adjustable resistances R² and R³ connected in series across the output terminals thereof. The grid 20^c of tube 20 is permanently connected to the negative output terminal of rectifier 23 through transformer coil 24^c and the grid 21^c of tube 21 is permanently connected to said output terminal through transformer coil 24^d. The cathodes 20^a and 21^a of tubes 20 and 21 are both connected to the positive output terminal of rectifier 23 through adjustable resistance R³. Adjustable resistance R² is normally shunted by contacts 17^c of relay 17.

As is apparent from the foregoing, the grids 20^c and 21^c of tubes 20 and 21 are both subjected to a negative grid bias by rectifier 23 which is of a given value when resistance R² is shunted by contacts 17^c of relay 17 and is of an increased value upon opening of said contacts. Also it is apparent that the grid 20^c of tube 20 is subjected to control by the voltage induced in transformer coil 24^c and that the grid 21^c of tube 21 is subjected to control by the voltage induced in transformer coil 24^d.

Referring to the graph shown in Fig. 2, the curve E¹ represents the potential impressed between the anode and cathode of one of the tubes 20 or 21 when contacts 16^c of relay 16 are in closed position, and the curve f represents the control characteristic of the tube, that is the potential which must be impressed on the grid, in order to render the tube conducting. Also in Fig. 2, E¹ represents the negative bias to which the grid of each tube is subjected when resistance R² is shunted by contacts 17^c of relay 17, and E² represents the negative bias to which the grid of each tube is subjected upon opening of said contacts. The curves E¹¹ and E²¹ represent grid voltages which are induced in transformer 22, the curve E¹¹ representing the induced grid voltage which is required to render the tube conducting when the negative grid bias is of the value E¹ and the curve E²¹ representing the induced potential which is required to render

the tube conducting when the negative grid bias is of the value E².

The function and operation of the aforescribed controller will now be more fully set forth. If the elevator car is standing still and the operator desires to move it in a downward direction he throws the car switch CS into its D position, thereby completing a circuit from line L¹ by conductor 26, to stationary contact 5, through contacts 10 and 12, to stationary contact 7, through the operating winding 2^a of reversing switch 2 to line L³. Switch 2 thus responds and in responding the same establishes power connections for releasing brake B and for causing operation of motor M in its down direction. Also upon movement of the car switch CS into its D position relay 16 is energized by a circuit extending from line L¹ by conductor 26, to stationary contact 5, through contacts 10 and 14, to stationary contact 8 and through the operating winding 16^a of said relay to line L³. Relay 17 responds upon closure of relay 16, the same being energized by a circuit extending from line L¹ by conductor 27, through auxiliary contacts 2^b of reversing switch 2, through contacts 16^b of relay 16 and through the operating winding 17^a to line L³. The contacts 16^c of relay 16 are thus opened to disconnect tubes 20 and 21 from the secondary windings of transformers T¹ and T², and also the contacts 17^c of relay are opened to include resistance R² between the output terminals of rectifier 23 whereby the tubes 20 and 21 are subjected to the negative grid bias E² shown in Fig. 3.

Assume that the elevator car is moving downwardly toward landing F. During movement of the elevator car toward such landing, the lower and center legs of core member 24 of transformer 22 are bridged by armature 25 and a voltage is then induced in the coil 24^d which is sufficiently positive to render tube 21 conducting at the beginning of the half cycle when the anode of said tube is positive with respect to the cathode. If the car switch CS is now returned to off position the aforescribed energizing circuit for down reversing switch 2 is interrupted and relay 16 is also immediately deenergized to establish circuit between transformers T¹ and T² and the cathodes of tubes 20 and 21. Since tube 21 is now rendered conducting by current induced in coil 24^d relay 19 will be energized by current from transformer T². Relay 19 thus responds and down reversing switch 2 is maintained energized by a circuit extending from line L¹ to stationary contact 5 through movable contacts 10 and 15 to stationary contact 9 and through relay 19 and the operating winding 2^a of switch 2 to line L³. Upon dropping out of relay 16, relay 17 is maintained energized by a circuit extending from line L¹ by conductor 27, through auxiliary contacts 2^b of reversing switch 2, through contacts 17^b of relay 17 and through the operating winding of said relay to line L³.

As the elevator car moves nearer to the landing F the lower leg of transformer core 24 moves away from the armature 25 and the induced voltage in coil 24^d is thus reduced. When the elevator car is a predetermined distance above landing F the induced voltage in coil 24^d is reduced to a value which renders tube 21 non-conducting and relay 19 is thus deenergized to interrupt the aforescribed maintaining circuit for down reversing switch 2. Upon opening of reversing switch 2 motor M is deenergized and

is brought to rest under the action of its associated brake B.

As is apparent, for a given elevator speed the distance which the elevator car travels upon opening of reversing switch 2 is proportional to the load in the elevator car. Also as is apparent, by adjusting resistance R² the negative grid bias E² may be varied to vary the point at which reversing switch 2 is deenergized during approach of the elevator car to floor landing F. In accordance with the present invention resistance R² is adjusted to provide for opening of reversing switch 2 at such a point above the landing F that the elevator car C is brought to rest substantially level with landing F under normal or average load conditions.

Upon opening of down reversing switch 2, the above described maintaining circuit for relay 17 is interrupted. However, relay 17 is provided with suitable means for delaying opening movement thereof until after motor M is brought to rest under the action of brake B. Upon opening of relay 17 the contacts 17^c thereof close to shunt resistance R², and upon shunting of resistance R² the grids 20^c and 21^c of tubes 20 and 21 are subjected to the negative grid bias E¹ shown in Fig. 2.

Assume that the elevator car during downward travel is stopped short of landing F with a load lighter than the normal or average load. Tube 21 is now subjected to the negative grid bias E¹ (Fig. 2) and sufficient voltage is induced in coil 24^d to again render said tube conducting for re-closure of relay 19. Thus reversing switch 2 is energized to effect downward operation of motor M. When the elevator car moves into a position substantially level with landing F the induced voltage in coil 24^d will be less than the induced voltage E¹ represented in Fig. 2 whereby the tube 21 is again rendered non-conducting. Relay 19 is then deenergized and the elevator car is stopped in a position level with the landing F.

Assume now that the load in the elevator car exceeds the normal or average load and that the car overtravels downwardly beyond the landing F. The armature 24 will be so located with respect to core 24 that the reluctance of the upper magnetic path is less than that of the lower path. Under this condition the voltage impressed on the grid 21^c at the beginning of the positive half cycle is negative but the voltage of the grid 20^c during the beginning of the same half cycle is positive. Tube 20 is now subjected to the negative grid bias E¹ (Fig. 2) and the voltage induced in coil 24^c is sufficient to render said tube conducting. Relay 18 will thus be energized by current from transformer T¹ and upon response of said relay up reversing switch 1 is energized by a circuit extending from line L¹ by conductor 26 to stationary contact 5, through movable contacts 10 and 15, to stationary contact 9, through relay 18 and through the operating winding 1^a of said reversing switch to line L². Upon closure of reversing switch 1 the elevator car moves upwardly and when the same is level with landing F the induced voltage in coil 24^c is reduced to a value which renders tube 20 non-conducting. Relay 18 is then deenergized and the elevator car is stopped in a position substantially level with the landing F. As is apparent, re-leveling operations by the relays 18 and 19 are relatively short so that motor M irrespective of its normal speed cannot gain any appreciable velocity. The elevator car is thus brought

to rest level with the landing by a single re-leveling operation.

Upon movement of the car switch CS into its up position, up reversing switch 1 is energized by a circuit extending from line L¹ to stationary contact 5, through contact segments 10 and 11 to stationary contact 6, and through the operating winding 1^a of reversing switch 1 to line L³. Also upon movement of car switch CS into its U position relay 16 is energized by a circuit extending from line L¹, by conductor 26, to stationary contact 5, through movable contact segments 10 and 13 to stationary contact 8 and through the operating winding 16^a of said relay to line L³. Closure of relay 16 establishes the aforescribed energizing circuit for relay 11. Upon return of car switch CS to off position, during upward movement of the elevator car, tube 20 acts in substantially the same manner as does tube 21 during downward movement of the elevator car to deenergize motor M at a predetermined distance from landing F. Thereafter the tubes 20 and 21 act as hereinbefore described to effect a re-leveling operation if the elevator car over-shoots or stops short of the landing.

What I claim as new and desire to secure by Letters Patent is:

1. An electric elevator system comprising, in combination, a control switch for effecting operation of the elevator car in opposite directions selectively, of leveling means for controlling the operation of said car when said switch is returned to off position and the car is near a landing, said leveling means including two gaseous electron discharge tubes, one for each direction of operation of said car, each of said tubes having a grid, a transformer having relatively movable parts, one part mounted on the car and the other part located at a landing and adjacent to the path of said first part, said transformer having a primary winding connected to an alternating current source and a secondary winding arranged to have induced therein a voltage, the magnitude of which varies in accordance with the position of the car relative to said landing, means for subjecting said grids to said varying voltage and to a biasing potential of given value upon return of said switch to off position to provide for continued operation of the car until the same moves into a predetermined zone at said landing, and means acting upon stopping of said car within said zone for subjecting said grids to said varying voltage and to a second biasing potential which provides for a leveling operation of the car upon failure of the same to stop substantially level with said landing.
2. In an electric elevator system, in combination, a control switch for effecting operation of the elevator car in opposite directions selectively, electric valve means for controlling the operation of said car when said control switch is returned to off position and said car is near a landing, means for supplying a control voltage which varies in accordance with the position of said car when said car approaches said landing, and means for subjecting said valve means to control by said varying voltage and also to control by a biasing potential of given value to render said valve means effective to continue operation of said car until the same moves into a predetermined zone at said landing, and means for reducing said biasing potential upon stopping of said car within said zone to provide for re-starting of said car upon failure of the same

to stop within a relatively narrow zone located within said former zone.

3. In an electric elevator system, in combination, a control switch for effecting operation of the elevator car in opposite directions selectively, a transformer having relatively movable parts, one part being mounted upon said car and the other being located at a landing and adjacent to the path of said first part, said transformer having primary and secondary windings so arranged that a voltage is induced by the former in the latter which varies in accordance with the position of said car relative to said landing, electric valve means for controlling the operation of said car when the same is near said landing and said control switch is returned to off position, means for subjecting said valve means to control by said varying voltage and also to control by a biasing potential of given value to render said valve means effective to continue the operation of said car until the same moves into a predetermined zone at said landing, and means acting upon stopping of said car in said zone to modify the value of said biasing potential and thereby render said valve means effective to provide a leveling operation of said car upon fail-

ure of the same to stop substantially level with said landing.

4. In an electric elevator system, in combination, an elevator car, a motor for driving said car, a reversing controller for said motor including a control switch for establishing and interrupting hoisting and lowering power connections for said motor selectively, means for supplying a control voltage which varies in accordance with the position of said car with respect to a landing, electric valve control means for controlling the operation of said car when said control switch is returned to off position and said car is near said landing, and means for subjecting said valve means to control by said varying voltage and also to control by a biasing potential of given value to render said valve means effective to continue operation of said car until the same moves into a predetermined zone at said landing, and means for varying said biasing potential upon failure of said car to stop within a narrow dead zone located within said former zone to render said valve means effective to restart said car for movement into said latter zone.

EVIND U. LASSEN.
